N.J.

Filed June 10, 1960, Ser. No. 35,245
10 Claims. (Cl. 219—39)

The present invention relates generally to improvements in heating apparatus, and it has specific relation to a combination space heater and light.

There are many different kinds of space heaters on the market using infra-red electric bulbs in combination with a fan for providing a source of auxiliary heat in the form of a space heater, but none of them is very efficient or capable of using the light generated by said bulb to illuminate the room in which it is being used.

With the present invention there is provided a very efficient and extremely inexpensive combination space heater and light which overcomes all of the disadvantages of the aforementioned heaters.

An object of the present invention is to provide a simple, inexpensive and efficient combination space heater and light.

Another object of the invention is the provision of a combination space heater and light which is simple, durable and economical to use, requiring no special electrical outlets or special heavy duty lead-in cords of the type required by most electrical heating appliances.

A further object of the invention is to provide a simple, efficient, durable and extremely light-in-weight combination space heater and light, which is not only inexpensive to operate but which has means for controlling the amount of light to be given off without reducing the amount of heat to be discharged therefrom.

Another object of the invention is the provision of a translucent space heater which will give off sufficient light to illuminate a room with a soft, subdued glow, especially suitable for television viewing.

A further object of the invention is to provide a combination space heater and light which has a sealed heating unit that is safe and efficient to use in that paper or other flammable material dropped accidentally or placed against it by children will not be set on fire.

Another object of the invention is the provision of a combination space heater and light which has a sealed heating unit that is safe and explosion proof when used around flammable vapors, such as vapors from paints, solvents, etc.

A further object of the invention is to provide a combination space heater and light which can be used with a conventional light bulb in the summer time as a combination filter and light instead of a combination heater and light.

Another object of the invention is the provision of a heater and light wherein the incoming air will be preheated by the heat radiating from the heater casing before being passed over said heating elements.

Another object of the invention is to provide a casing for a space heater and light wherein the casing may be made of a colored translucent material, whereby the light emitted by said heater will take on the color of the casing.

Other and further objects and advantages of the invention, which result in simplicity, economy and efficiency, will be apparent from the following detailed description, wherein but three preferred forms of embodiment are shown, reference being had to the accompanying drawings, forming a part hereof, wherein like numerals indicate like parts, in which:

FIGURE 1 is a vertical sectional view of a combination space heater and light showing one embodiment of the invention;

2

FIGURE 2 is a cross-sectional view taken substantially along the line 2—2 of FIGURE 1, the same looking in the direction of the arrows;

5 FIGURE 3 is a modified form of combination heater and light wherein a plurality of heat and light sources are combined, and the combination is equipped with an air purifier and humidifier;

10 FIGURE 4 is a vertical sectional view of another modified form of combination space heater and light, which comprises a double walled casing of translucent material whereby the incoming air is passed between said walls to preheat the same before it is passed over said heating elements.

15 Referring now to the drawings and particularly to FIGURES 1 and 2, there is shown a combination space heater and light which comprises an opaque housing 10, having upstanding sidewalls 11, 12, 13 and 14, a removable closed bottom 16 and a movable top 17. The housing 10 may be made of wood, preformed fiber board, metal, plastic or any other suitable materials that are light-in-weight, durable and inexpensive. The bottom 16 is attached in any suitable manner, as by screws, so that it can be removed for servicing and cleaning the fan.

20 The housing 10 is provided with a plurality of horizontal openings 21 in its sidewalls adjacent its bottom 16, which are adapted to serve as an inlet or intake for the air being drawn thereinto by the fan for heating. Obviously, any other form of opening may be employed that is suitable for the rapid intake of air thereinto. The housing 10 is also provided with an air outlet 22, which is likewise shown as a series of horizontal apertures or perforations 22 through the side 12 of the housing 10 adjacent its top. Manifestly, the air outlet 12 may be provided in any other suitable form, which will permit 25 the rapid discharge of heated air from the housing 10 in any desired direction.

30 A conventional ventilating fan 26 is required to draw the air into the housing 10 through the intake opening 21, move it over the source of radiant energy and discharge it from the air outlet 22. Preferably, it should be mounted within the housing 10 and on the bottom 16 adjacent the air intake openings 21, whereby the outside air may be quickly and efficiently drawn into the housing 10. The fan 26 is electrically operated, and receives 35 its electricity from an outside source of supply (not shown) through a conventional electric cord 27, having a plug 28, which can be inserted in any standard electric outlet (not shown).

40 A source of radiant energy, which is shown in the form of a projecting infra-red bulb 31, is used as the heating and lighting unit. The reflector bulb 31 may be mounted within the housing 10 in any suitable manner. In the present arrangement, it is mounted in a vertically extending socket member 32, which, in turn, is mounted 45 on a horizontal removable supporting platform 33, having a plurality of spaced apertures or perforations 34 extending vertically for permitting the rapid passage of unheated air forced by the blades 25 of the fan 26 upwardly therethrough.

50 Mounted above the source of radiant energy 31 is a suitable removable and replaceable transparent or translucent air filter and heat exchange unit 36. The most efficient transparent and/or translucent heat exchange unit 36 known to date is spun fiber glass, having a density of 5.57 ounces per cubic foot by weight. Fiber glass is sold on the open market in bulk and in various sizes of preformed bats of various thicknesses. These bats can be cut with a shears to any size desired. The air filter and heat exchange unit 36 shown in the drawings 55 is made up of two such bats 37 and 38, having a cross-sectional area equal to the cross-sectional area of the housing 10, and a combined thickness of approximately 60

four inches. The filter unit 36 is so light-in-weight that very little horizontal support is required. In the illustrations shown in the drawings, the heat exchange unit 36, consisting of the filtering bats 37 and 38, is positioned on a rigid wire mesh screen 39, which, in turn, is supported by angle iron brackets 41 and 42 mounted on and extending along opposite sidewalls 11 and 12. This screen support 39 will prevent the heat exchange unit 36 from being jarred down onto the bulb 31 and becoming scorched or melted.

The fan 26 and infra-red bulb 31 are connected in parallel to the source of electrical energy, whereby both will be operating at the same time wherever the plug 28 is electrically connected to said source of electrical energy.

Referring now to FIGURE 3, there is shown a modification which the invention may assume, wherein a plurality of individual sources of light projecting radiant energy infra-red bulbs are used for increasing the capacity of the heater. In this arrangement, the heater housing 50 has been subdivided by a vertical partition 51, extending from the bottom 52 of the housing to the top of the heat exchange unit or filters 53 and 54, forming two vertically extending heating chambers 56 and 57, each chamber having its own source of radiant energy 58 and 59.

In this modification, the closed bottom 52 is provided with feet 61, which raise it off the floor, and the air intake openings 62 are vertically extending apertures through that part of the bottom surrounding the fan 26. The top of the housing 50 is closed by a removable glass or plastic baffle plate member 64, which is supported by brackets 41 and 42 and permits light to pass therethrough but not the heated air stream passing through the heat exchange unit or filter 53. The moving air stream is deflected downwardly by the baffle plate 64 and through the second heat exchange unit or filter 54, which, in turn, is heated by a second infra-red projecting bulb 59. In passing through the second heat exchanger 54, the heated air absorbs more heat, whereupon it passes through the apertures 34 of the supporting platform 33, passing over a pan of water 66, thereby absorbing moisture. The heated air then passes out through the rotatable circular air outlet 67. By making the air outlet 67 rotatable, it can be turned so as to direct the heated discharged air in any desired direction. When turned upwardly, as shown in FIGURE 3, the heater 50 may be used as a convenient hair dryer.

The fan 26, the infra-red projecting bulbs 58 and 59, and the ozone bulb 68, which serves as an air purifier, are to be connected electrically in parallel so that when the plug 28 of the cord 27 is suitably connected to a source of electrical energy all will be operating at the same time.

Referring now to FIGURE 4, there is shown another modification in which the heating elements are similar to those shown in FIGURE 3, but the housing 70 is made of a spaced double walled construction, whereby the incoming air will be passed between said walls and over and around the inner casing for preheating before reaching the fan 26. If the housings are made of compacted fiber glass or plastic having non-burning or non-scorching properties, the material may be colored before forming in which event the finished heater will be either transparent or translucent and capable of emitting a soft subdued colored light or glow throughout its entire surface area.

The housing 70 consists of an inner casing 71 and an outer casing 72. The inner casing 72 is subdivided by a vertically extending partition 73, extending from the bottom 74, which is provided with feet 76, to the top of the heat exchangers 77 and 78, forming two vertically extending heating chambers 81 and 82. Each chamber 81 and 82 has its own source of radiant energy 83 and 84. The radiant energy bulbs 83 and 84 are General Electric G.E. 30, bulbs, having no built-in reflector but a shape similar to a conventional electric light bulb, where-

by heat and light is projected in all directions. With this type of bulb, a wire cage or screen 85 is mounted around each of the bulbs 83 and 84. Since the heat and light is being transmitted laterally as well as upwardly, increased heating capacity can be obtained by filling the space around the wire cage or screen 85 with bulk fiber glass 87, which is in addition to the heat exchange units 77 and 78.

In this construction, the air intake is through an opening 88 in the top of the outer casing 72, and passes downwardly through the passageway 89 between said outer casing 72 and inner casing 71. The air is passed through apertures 91 in the lower ends adjacent the closed bottom 74 of the sidewalls of the inner casing 71 and the partition 73 into the fan chamber 92. By drawing the incoming air through the opening 88 in the outer casing 71, it is passed over the outer surfaces of the inner casing 72, which is quite hot due to its heated inner chambers 81 and 82. In this manner the incoming air is preheated before being passed into the fan 26. The open top 93 of the inner casing 72 is closed with a removable flat baffle plate 94, which may be made of glass, plastic or any other suitable transparent or translucent material. This baffle plate 94 serves to deflect the heated air from the chamber 81 towards the chamber 82, where it is further heated before being discharged through the discharge outlet 67. The space around the screen or wire cage 85 in the chamber 82 is likewise filled with bulk fiber glass 87. The heater 70 in FIGURE 4 is otherwise substantially identical to the heater 50 in FIGURE 3. The wiring for FIGURE 4 is shown diagrammatically, and it is not believed to be necessary to show it in detail. The fan 26 and the infra-red bulbs 83 and 84 are to be connected electrically in parallel so that each will be operating at the same times.

The size and capacity of the heaters will, of course, be dependent upon the size of the housing, the number of heating units, the size of the fan, the density and thickness of the filtering materials. These will be factors that will be readily understood and appreciated by one skilled in the art from the examples given hereinafter.

Extensive tests have been conducted with this type of combination heater and light, and they show very little loss of heat and light in passing through four inches of white or clear fiber glass positioned between the source of radiant energy and the top of the heater, as in FIGURES 1 and 3. Fiber glass can be made in any number of colors, and the light emitted from a heater having colored fiber glass filters will take on the color of such filters.

It will be appreciated that heaters using three 375 watt capacity infra-red bulbs may be used without endangering the capacities of an ordinary light outlet or a conventional light extension cord. Therefore, no heavy heating wire is required for an extension cord and no special outlet need be used. Tests have shown that two standard infra-red bulbs of 375 watt capacity will give off more usable heat under the conditions embodied in this type of heater than the conventional type space heaters using heating coils or calrod units, which require extra heavy electric cords and require 1,500 watts for efficient operation.

The heat exchange units and/or filtering material obviously must be made of transparent or translucent material in order to permit the passage of and diffusion of light therethrough. Many different kinds of material now on the market have been tried, but none except fiber glass has proven efficient. Manifestly, there may be other plastic or synthetic materials produced having all of the heat exchange and light transmitting properties desirable, which could be substituted for the present fiber glass without departing from the spirit or scope of the invention.

Fiber glass in bulk or in preformed bats is very inexpensive and exceedingly light-in-weight. It has no tendency to compact even under crushing weights, and, when

the weight is removed, returns substantially to its original condition and shape. The spun fiber glass threads do not burn, but under intense heat become scorched, turning dark and sometimes have a tendency to melt within the range of heat developed by a 375-watt infra-red bulb. Therefore, it is necessary to use a ventilating fan for forcing the air through the housing at all times when the light is turned on.

The fan should have sufficient capacity to remove the absorbed heat from the fiber glass filters before it becomes scorched. A conventional ventilating fan having a capacity of moving a stream of air at the rate of three hundred feet per minute is sufficient for one 375 watt infra-red bulb. Of course, fans having a higher or lower capacity might be used satisfactorily, but not efficiently.

The optimum is for the filter material to collect all of the heat being given off by the source of radiant energy, and a fan capable of removing it therefrom before it has an opportunity to build-up to a scorching temperature therein. The thickness of the filter bats need not be limited to that shown and described, but can be varied between a thickness of not less than one inch nor more than eight inches, depending upon the velocity or capacity of the fan being used. Obviously, if too thick a filter is used, an exceedingly large fan must be installed, which would make the heater expensive and inefficient to operate. If too thin a filter were to be used, an inefficient heat-exchange and filtering action would take place, as there would not be enough build-up of heat to provide heated air having a temperature capable of comfortable heating of the room in which it is to be situated. A comfortable and efficient heating temperature is one that increases the temperature of the incoming air in the order of 125 degrees F.

It will be obvious that, if too thick a filter is used, the light from the source of radiant energy cannot be transmitted and diffused therethrough, and that, if too thin a filter were to be used, too much light would be transmitted and diffused therethrough for providing a subdued light of the type desired.

While no filters are shown in the drawings over the air inlets, it will be apparent to those skilled in the art that the usable life of the transparent or translucent heat exchange and filtering units may be extended considerably if a disposable filter is mounted removably over said air inlets, whereby they may be changed easily and quickly when becoming dirty. Such filters would collect and remove most of the dust and dirt from the incoming air so that only clean filtered air will be passed through such units.

In the summer time, when filtering action and subdued light is desired but not heat, these heaters may be used efficiently for such purposes by merely replacing the infra-red bulbs with conventional low wattage incandescent bulbs. The heat generated by such bulbs will not be noticeable.

It will be obvious that the heaters 10, 50 and 70 illustrated are portable space heaters capable of being moved as desired. However, it must be realized that similar heaters may be built into or otherwise mounted around the walls of a room in a building to provide the necessary individual heating unit or units therefor. Such a use will materially reduce the cost of equipping a building with a good heating system as compared to present day conventional central heating systems.

Although we have described in detail and illustrated in the drawings but three forms which the invention may assume, it will be readily apparent to those skilled in the art that the same need not be so limited, but that various modifications may be made therein without departing from the spirit thereof or from the scope of the appended claims.

What we claim is:

1. A combination heater and light which comprises an enclosed housing having an air intake and an air out-

let, a source of radiant energy capable of producing heat and light mounted within said housing between said air intake and said air outlet, a filter of heat absorbing and light transmitting material mounted within said housing between said source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, a light transmitting area in said housing for allowing the diffused light rays passing through said filter to pass out of said housing, and means for moving a stream of air over said source of radiant energy and through said filter to remove the absorbed heat therefrom and discharge it through said air outlet.

2. A combination heater and light which comprises an enclosed housing having an air intake and an air outlet, a source of radiant energy capable of producing heat and light mounted within said housing between said air intake and said air outlet, a filter of heat absorbing and light transmitting material mounted within said housing between said source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, means for moving a stream of air over said source of radiant energy, a light transmitting area in said housing for allowing the diffused light rays passing through said filter to pass out of said housing, and through said filter for removing said absorbed heat for discharge through said air outlet, and means adjustably mounted above said filter for reflecting the diffused light from said filter outside of said housing and into the surrounding area.

3. A combination heater and light which comprises an enclosed housing made of translucent material having an air intake and an air outlet, a source of radiant energy capable of producing heat and light mounted within said housing between said air intake and said air outlet, a filter of heat absorbing and light transmitting material mounted within said housing between said source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, and means for moving a stream of air over said source of radiant energy and through said filter to remove the absorbed heat for discharge through said air outlet.

4. A combination heater and light which comprises an enclosed housing made of translucent material having an air intake and an air outlet, a source of radiant energy capable of producing heat and light mounted within said housing between said air intake and said air outlet, a heat absorbing and light transmitting filter of spun translucent fiber glass mounted within said housing between said source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, and means including a circulating fan mounted between said air intake and said source of radiant energy for moving a stream of air over said source of radiant energy and through said filter to remove the absorbed heat for discharge through said air outlet.

5. A combination heater and light which comprises an enclosed housing having an air intake and an air outlet, a source of radiant energy capable of producing heat and light mounted within said housing between said air intake and said air outlet, a heat absorbing and light

transmitting fiber glass filter mounted within said housing between said source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, means for moving a stream of air over said source of radiant energy and through said filter to remove the absorbed heat therefrom for discharge through said air outlet, and a light transmitting area in said housing for allowing the diffused light rays passing through said filter to pass out of said housing.

6. A combination heater and light which comprises an enclosed housing made of non-burning and non-scorching material having an air intake and an air outlet, a plurality of sources of radiant energy capable of producing heat and light mounted within said housing between said air intake and said air outlet, a filter of heat absorbing and light transmitting material mounted within said housing between each source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, a light transmitting area in said housing for allowing the diffused light rays passing through said filter to pass out of said housing, and means for moving a stream of air over said sources of radiant energy and through said filters to remove the absorbed heat therefrom for discharge through said air outlet.

7. A combination heater and light which comprises a double walled translucent housing forming an outer chamber and an inner chamber, an air intake including the outer chamber, whereby the air entering said intake will be preheated while passing through said outer chamber and into said inner chamber, an air outlet connected with said inner chamber, said inner chamber being subdivided into a plurality of heating chambers arranged in series, each heating chamber having a source of radiant energy capable of producing heat and light, each heating chamber having a filter mounted between each source of radiant energy and its air outlet capable of absorbing the heat and diffusing the light therethrough, said filters having a density and thickness capable of filtering the air passing therethrough without substantially impeding its progress while permitting a substantial amount of diffused light to pass therethrough, and means for moving a stream of preheated air through said heating chambers and over said sources of radiant energy and through said filters to remove the absorbed heat therefrom for discharge through said air outlet.

8. A combination heater and light which comprises an enclosed housing made of an opaque material having an air intake and an air outlet and an opening in its top, a source of radiant energy capable of producing heat and light mounted within said housing between said air intake

10 5 20 25 30 35 40 45 50

and said air outlet, a heat absorbing and light transmitting fiber glass filter mounted within said housing between said source of radiant energy and said air outlet capable of absorbing the heat and diffusing the light therethrough, said fiber glass filter having a density and thickness capable of filtering the air passing therethrough without substantially impeding its progress while at the same time permitting a substantial amount of diffused light to pass therethrough, means for moving a stream of air over said source of radiant energy and through said filter to remove the absorbed heat therefrom for discharge through said air outlet, a removable translucent baffle closing said opening in its top, and an adjustable closure mounted above said baffle for reflecting the light passing through said baffle into the surrounding area.

9. A combination heater and light which comprises an enclosed housing made of a non-scorching, non-burning colored translucent material having an air intake and an air outlet, a source of radiant energy capable of producing heat and light mounted within said housing between said air intake and said air outlet, a filter of heat absorbing and light transmitting material mounted within said housing between said source of radiant energy and said air outlet capable of absorbing the heat and diffusing the light therethrough, said filter having a density and thickness capable of filtering the air passing therethrough without substantially impeding its progress while permitting a substantial amount of diffused light to pass therethrough, and means for moving a stream of air over said source of radiant energy and through said filter to remove the absorbed heat therefrom for discharge through said air outlet.

10. A combination heater and light which comprises an enclosed housing having an opening in its top and an air intake and an air outlet, a source of radiant energy capable of producing heat and light mounted within said housing between said air inlet and said air outlet, a filter of heat absorbing and light transmitting material mounted within said housing and surrounding said source of radiant energy capable of absorbing the heat and diffusing the light therethrough, said filter having a density and thickness capable of filtering the air passing therethrough without substantially impeding its progress while permitting a substantial amount of diffused light to pass therethrough, means for moving a stream of air through said filter to remove the absorbed heat therefrom and discharge it through said air outlet, and a transparent baffle for closing the opening in its top to deflect the heat while permitting the diffused light to pass out of said housing.
